US0D1076414S

(12) United States Design Patent (10) Patent No.: US D1,076,414 S
(45) Date of Patent: * May 27, 2025

(54) EMERGENCY HANDBAG

(71) Applicant: Hebei Be-Better Bag Manufacturing Co., Ltd., Gaobeidian (CN)

(72) Inventor: Yang Li, Gaobeidian (CN)

(73) Assignee: Hebei Be-Better Bag Manufacturing Co., Ltd., Baoding (CN)

() Term: 15 Years

(21) Appl. No.: 29/911,648

(22) Filed: Sep. 6, 2023

(30) Foreign Application Priority Data

Jun. 13, 2023 (CN) 202330361210.3

(51) LOC (15) Cl. 03-01

(52) U.S. Cl.
USPC D3/203.6
